UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING ORE AND THE LIKE.

Application filed April 13, 1921. Serial No. 460,865.

To all whom it may concern:

Be it known that I, CHARLES E. DAVIS, a citizen of the United States, residing at Chicago, in the county of Cook and State of Illinois, have invented an Apparatus for Handling Ore and the like, of which the following is a specification.

This invention relates to improvements in apparatus for handling ore and the like and has for its principal object to provide a simple and durable conveying apparatus for transporting loose material from one place to another as for instance in a mine.

In a prior application, Serial No. 382,696, filed May 20, 1920, I have disclosed an apparatus of the class above described comprising a scraper and a movable frame adapted to form a support about which said scraper is guided. In the present application, I utilize the same general principles of construction and operation as therein described, but provide certain improvements in the construction of the guiding frame and the scraper used therewith, as will hereinafter more fully appear.

My invention may best be understood by reference to the accompanying drawings in which Figure 1 is a top plan view of my improved apparatus in working position. Figure 2 is a detail. Figure 3 is a side view of the apparatus. Figure 4 is a vertical cross-section taken on line 4-4 of Figure 1. Figure 5 is a vertical cross-section taken on line 5-5 of Figure 1. Figure 6 is a top plan view of the scraper. Figure 7 is a side view of the scraper.

In the embodiment of my invention illustrated, the apparatus is adapted for use in mining operations in which loose material is to be transported from the working face, or place from which the material is being mined, to a place where it may be loaded on mine cars or the like. The loading apparatus comprises a scraper 1 adapted to be moved on the mine bottom by means of flexible draft cables 2 and 3, and about a guiding frame 4 adapted to be fixed on the mine bottom in position to form a bearing for one side of the scraper as the latter is advanced into the loose material. The frame 4 is held in place by means of a guiding device such as a pair of mine jacks 5 and 5^a of the usual type which are inserted in a longitudinally disposed slot 6 formed in the frame.

The jacks 5 and 5^a are spaced apart so as

to guide the movement of the frame in a longitudinal direction. The frame may be moved by any suitable means such as a draft device attached to one of the jacks. In the embodiment illustrated, the draft device comprises a chain 11, hooked to the forward jack 5, and operated by a ratchet wheel 8 mounted on the forward end of the frame and at one side thereof. Said ratchet wheel may be manually operated by a handle 9, and is connected with a sprocket 10 about which the chain 11 is trained. Said chain is preferably made up of two portions, the forward portion 12 of which comprises roller-links 13, 13 adapted to engage the teeth of the sprocket wheel 10, and the rear portion 14 of which comprises chain links 15, 15 of the ordinary type trained about a sheave 16 at the rear end of the frame 4 and from thence forwardly to a hook 17 which engages the forward jack 5. By means of this arrangement, the entire frame is movable in a longitudinal direction along the mine bottom so as to advance the scraper 1 as desired. The links 13, 13, may be readily disengaged from the sprocket 10 when it is desired to change the position of the frame with respect to the jacks.

The frame 4 is provided at its forward end with an arcuate shield or bearing member 18, a central frame member 19 and an end-piece 20. Said shield 18 is substantially semi-circular in shape and is preferably made of a single casting. A laterally extending lip 21 is provided at the lower margin of the shield 18, and has its upper surface beveled downwardly to form a cutting edge for digging under loose material, thereby tending to keep the forward end of the frame on the mine bottom as the frame is advanced. The upper end of the shield 18 preferably extends above the central frame member 19 of the frame and is provided with a grooved portion 22 around its upper end for the purpose of catching the draft ropes when they may accidentally be thrown upwardly along the shield during the operation of the device. The central frame member 19 of the frame comprises a plurality of longitudinally disposed beams 23, 23 and 24, 24 which form the longitudinal slot 6 in which the jacks 5 and 5^a are inserted, and outer beams 25, 25 and 26, 26. Said beams are connected together by a plurality of suitable supports 27, 27. The shield 18

is detachably connected to the central frame member 19 by means of bolts 28, 28. The end-piece 20 at the rear end of the frame is detachably connected to the frame member 19 by vertically disposed bolts 29, 29 on either side of the slot 6. Said end-piece is provided with an arcuate bearing surface 30 on one side thereof about which the scraper 1 may be moved when the frame is positioned at an angle to the normal path of movement of the scraper. A sheave 31 is mounted on the opposite side of said end-piece in position to be engaged with the draft rope 3 when the frame is positioned at an angle to the path of movement of the scraper as indicated in dotted lines in Figure 1. The arrangement is such that the bearing surface 30 and the sheave 31 are reversible, respectively, that is to say, they can be changed to the opposite side of the frame by inverting the connecting piece 20. With this arrangement a scraper may be operated from right to left or from left to right about the frame and at any desired angle thereto. Referring now to the improved form of scraper, details thereof are shown in Figures 6 to 17 inclusive, which illustrate a preferred form which I find to be particularly adapted for use with an apparatus such as hereinbefore described. The scraper 1 is bottomless and one side 32 thereof is longer than the opposite side 34. The central and forward wall portion of the longer side 32, indicated at 33, is curved to conform substantially with the curvature of the shield 18. The opposite or outer side 34 of the scraper has its central and forward wall portion 35 laying in an arc having substantially the same center of curvature as that of the opposite wall portion 33; in other words, the curved portions of the scraper are substantially concentric with each other, and with the bearing shield 18. With this concentric relation, it will be seen that the outer wall of the scraper cuts into the loose material in a curved direction controlled by the center of curvature of the shield 18, thus offering a minimum amount of resistance to the scraper as it collects the material. A horizontal lip 36 extends forwardly and inwardly from the forward vertical margin or cutting edge 37 of the outer wall 34, and has its upper surface beveled downwardly, forming in effect a knife edge for digging into the loose material, thereby tending to direct the course of the scraper in a horizontal plane and control and stabilize the movement of the scraper as it is moved about the shield. A similar projection 36^a is preferably provided at the forward end 43 of the opposite wall 32. The rear wall of the scraper comprises a substantially vertical portion 39, and an inclined portion 40 extending downwardly to the bottom margin 41 of the scraper, as shown in Figure 7. The

purpose of this conformation is to allow the scraper to be lifted over material which may be piled in the way of the scraper as it is moved rearwardly. The side walls 32 and 34 are each substantially upright at the forward end of the scraper, as shown in the figures, not only to provide suitable cutting edges as aforesaid, but to form a widely extended base for the scraper, thereby resisting any tendency of the latter to tip over. This tendency to tip over has been found to be particularly objectionable in a device of this character, because draft ropes are preferably attached eccentrically of the scraper, as will hereinafter be more fully described. The lower margins of the side walls are turned inwardly, and merge into the inclined portion 40 as shown in Figure 6, so that the material is readily gathered from the bottom, and yet may be discharged from the open bottom of the scraper as the latter is moved over an open loading chute or the like.

The draft ropes are attached to the scraper eccentrically thereof, the forward draft rope 2, usually called the drag line, being suitably attached to the inner wall 32 of the scraper by means of an eye 42, or its equivalent, preferably fixed on the inner face of the wall 32, and adjacent the forward margin 43 thereof. The rear draft rope 3 termed the tail-rope, is attached to the rear of the scraper but preferably eccentric with respect to the approximate longitudinal axis of the scraper, as shown in Figure 1. By connecting the drag line 2 to the inner wall 32 as indicated it will be observed (in Fig. 1) that as the scraper is moved about the shield 18 the drag line contacts with the forward edge 43 of the scraper and thereby exerts a maximum leverage in turning the scraper about the shield and maintains the scraper in contact therewith. On the other hand when the scraper is being moved forwardly out of contact with the frame in the position shown in Figure 6, it will be observed that the scraper is moved substantially in line with its longitudinal axis, rather than at an excessive angle thereto, as would be the case if the drag line were attached at the margin 43.

The use and operation of the apparatus above described is as follows:

The guiding frame 4 is positioned adjacent the pile of material to be moved or transported, and the draft ropes are connected with the winding engine suitably located to move the scraper toward the loading chute or place where the material is to be unloaded. The scraper is pulled rearwardly with the tail rope 3 about the guiding frame until the open end of the scraper faces the pile of material. The movement of scraper is then reversed by releasing the tail rope 3 and pulling the drag rope 2. The

scraper is loaded and it moves forward about the curved bearing member 18 with one side in lateral engagement therewith as shown in Figure 1.

5 The scraper then passes from the frame to the loading chute. After the scraper is unloaded it is returned to its initial position ready to collect another load. As the material within reach of the scraper is collected 10 the frame 2 is moved forward by means of the draft device comprising the chain and ratchet 8 or its equivalent, to advance the scraper toward the pile. The frame 4 may be moved in various positions, and angles 15 with respect to material to be moved by fixing the guiding means as desired.

Having described my invention what I claim as new and desire to cover by Letters Patent, is:

20 1. In a scraping apparatus, the combination of a frame having a curved bearing portion, a draft-operated scraper provided with lateral bearing means on one side adapted to have lateral engagement with 25 said curved portion, an opposite side having an upright cutting edge, and a horizontally disposed lip or cutting edge projecting forwardly from the bottom end of said upright cutting edge.

30 2. In a scraping apparatus the combination of a frame having an arcuate bearing portion, a draft-operated scraper provided with one side adapted to have lateral engagement with said arcuate portion, and an 35 opposite side provided with an upright cutting edge, both of said sides having arcuate portions substantially concentric with said arcuate bearing portion of the guiding frame.

40 3. In a scraping apparatus, the combination of a draft-operated scraper, a frame provided with a curved portion adapted to afford lateral bearing for said scraper, and a horizontally disposed lip projecting later-

ally from the bottom edge of said curved 45 portion.

4. In a scraping apparatus, the combination of a frame having a curved bearing portion, a scraper having one side wall thereof curved to conform substantially with said 50 curved bearing portion, and draft means for said scraper attached to the inner side of said curved wall at a point removed from the forward margin thereof.

5. In a scraping apparatus, the combination of a draft-operated scraper, a frame provided with a curved portion adapted to afford lateral bearing for said scraper, a guiding device for said frame, and means for moving said frame with respect to said 60 guiding device comprising a ratchet device, a sprocket associated with said ratchet device, a flexible draft device adapted to be anchored at one end, and having a length of sprocket chain adapted to be removably engaged with 65 said sprocket.

6. In a scraping apparatus, in combination with a frame adapted to be fixed against lateral movement, a reciprocating scraper adapted to have lateral engagement with 70 said frame as it moves about the latter, and having substantially upright side walls, and a rear wall having a lower portion inclined forwardly, as and for the purpose described.

7. In a scraping apparatus, in combination with a frame adapted to be fixed against lateral movement, a reciprocating bottomless scraper adapted to have lateral engagement with said frame as it moves about the latter, and having substantially upright side walls, 80 and a rear wall having a lower portion inclined forwardly, and terminating in the lower margin of said bottomless scraper.

Signed at Chicago, in the county of Cook and State of Illinois, this eleventh day of April, A. D. 1921.

CHARLES E. DAVIS.
